DESIGN FOR A COLLAR HOLDER

Olof V. Anderson, Cowesett, R. I.

Application October 5, 1945, Serial No. 122,546

Term of patent 14 years

(Cl. D17—8)

To all whom it may concern:

Be it known that I, Olof V. Anderson, a citizen of the United States, residing at Cowesett, in the county of Kent and State of Rhode Island, have invented a new, original, and ornamental Design for a Collar Holder, of which the following is a specification, reference being had to the accompanying drawing, forming a part thereof.

Fig. 1 is a plan view of a collar holder showing my new design; and

Fig. 2 is a side elevational view thereof.

I claim:

The ornamental design for a collar holder, substantially as shown.

OLOF V. ANDERSON.
